UNITED STATES PATENT OFFICE.

JOHN HENRY STANTON, OF TORONTO, ONTARIO, CANADA.

FEED-WATER REGULATOR AND ALARM.

1,354,702.

Specification of Letters Patent. Patented Oct. 5, 1920.

Application filed December 11, 1919. Serial No. 344,226.

To all whom it may concern:

Be it known that I, JOHN HENRY STANTON, of the city of Toronto, in the county of York, Province of Ontario, Canada, have 5 invented certain new and useful Improvements in Feed-Water Regulators and Alarms, of which the following is a specification.

This invention relates to devices for 10 maintaining a substantially constant water level in steam boilers, and for giving a warning signal in case the water level falls below a predetermined point, and my object is to devise a simple and cheap device which 15 will give efficient service when used with boilers having large steaming capacity relative to their water content, such as are employed in steam motor vehicles.

I attain my object by means of the constructions hereinafter described and illustrated in the accompanying drawings in which—

Figure 1 is a vertical section of the device; and

Fig. 2 a cross section on the line *a—b* in Fig. 1.

In the drawings like numerals of reference indicate corresponding parts in the different figures.

1 is a tank, which will usually be formed in two or more sections suitably secured together. This tank must be of sufficient strength to withstand the full steam pressure of the boiler with which the device is 30 used. At its upper end the tank is provided with a connection 2 by means of which its interior may be brought into communication with the steam space of the boiler. At its lower end the tank will be connected with 35 the water space of the boiler well below the average water level of the boiler, and also with the feed water supply. Any suitable arrangements may be provided for this purpose. I prefer, however, to so arrange it 40 that the feed water enters the tank 1 directly, thus insuring that in the operation of the device no hot water from the boiler will be wasted.

In the drawing 3 represents a feed water 50 pipe suitably communicating with the interior of the tank, and provided with a branch 4 for connection with a boiler. The interior of the tank at the bottom is thus in communication with the interior of the 55 boiler through the branch pipe 4 and the upper part of the feed water pipe 3. From

the arrangements described, it follows that the water level in the tank 1 will always correspond exactly with the water level in the boiler.

Centrally of the bottom of the tank is formed a water outlet 5. This outlet is adapted to be controlled by the rod 6 which is so guided that it may move longitudinally of the tank. In the preferred arrangement 65 the upper end of the rod is movable in the guide 7 formed on or secured to the top of the tank. The vertical movement of the rod is preferably limited by means of the collar 8 suitably secured to the rod and adapted 70 to engage the lower end of the guide 7. The inner end of the water outlet 5 is shaped to form the valve seat 9, and the lower end of the rod is suitably shaped to form a valve 75 engaging this seat.

Slidably supported on the rod is the closed float 10. The upward movement of the float relative to the rod is limited by the collar 11, which is adjustable on the rod by means of a set screw 12, the setting of the collar depending on the water level in the boiler it is desired to maintain. Ordinarily the pump or other feed water supply device is operated at a rate somewhat in excess of the requirements of the boiler. It results then 85 that the water level in the boiler and in the tank tends to rise above a predetermined position. Any rise in the water level above this position, however, causes the float to lift the rod 6 by engagement with the collar 11 and thus opens the water outlet 5 so that a certain proportion of the water pumped to the tank and boiler is by-passed back to the source of supply. The instant, however, 90 the water level falls below the normal, the float drops and the water outlet is closed until such time as the supply of water exceeds the demand. It is necessary in addition to regulating the water supply to also provide means for giving an alarm in case 95 the supply of water fails or becomes less than the amount being evaporated in the boiler. For this purpose I provide a jet 13 of small bore, which extends through the side of the tank from the interior, and is 100 controlled by a cock 14 of ordinary construction also located within the tank. The stem 15 of this cock has a toothed quadrant 16 secured thereto, which quadrant meshes with the rack 17 secured to the float extending parallel to the rod 6. When the water 110 level begins to go down, the first result is

- that the rod 6 drops and closes the water outlet 5. If the water level continues to fall, the float moves downwardly on the rod 6 and through the medium of the rack and 5 quadrant turns the cock and allows a jet of steam to escape through the jet 13, which may be used in any way to give the operator warning that the water level in the boiler has fallen to a dangerous extent.
- 10 From the above description it will be seen that I have devised a water regulator and alarm which will satisfactorily attain the object of my invention as set out in the preamble to this specification.
- 15 What I claim as my invention is:—
1. A feed water regulator and alarm for steam boilers comprising a tank adapted at its upper end for connection with the steam space of a boiler and at its lower end for 20 connection with the water space of a boiler and having a water outlet at its lower end; a rod suitably guided to move vertically in the tank and having its lower end adapted to control the water outlet; a float 25 slidable on the rod; a steam jet extending through the side of the tank; a cock within the tank controlling the jet; and connections whereby the falling of the float below a predetermined level moves the cock to open the jet.
  - 30 2. A feed water regulator and alarm for steam boilers as set forth in claim 1 in which a valve seat is formed at the inner end of the water outlet and the lower end of the rod is formed as a valve adapted to engage 35 said seat.
  3. A feed water regulator and alarm for steam boilers as set forth in claim 1 in which the tank is provided with a direct connection with a feed water pipe.
4. A feed water regulator and alarm for 40 steam boilers as set forth in claim 1 in which the operating connections between the float and the cock comprise a toothed quadrant secured to the stem of the cock and a toothed rack secured to the float and engaging said 45 quadrant.
5. A feed water regulator and alarm for steam boilers comprising a tank adapted at its upper end for connection with the steam space of a boiler and at its lower end for 50 connection with the water space of a boiler, and having a water outlet at its lower end; a rod suitably guided to move vertically in the tank and having its lower end adapted to control the water outlet; and a float 55 adapted to lift said rod but slidable thereon below its rod lifting position; and a steam passage adapted to be opened by the fall of the float relative to the rod.
6. A feed water regulator and alarm for 60 steam boilers comprising a tank adapted at its upper end for connection with the steam space of a boiler and at its lower end for 65 connection with the water space of a boiler, and having a water outlet at its lower end; a rod suitably guided to move vertically in the tank and having its lower end adapted to control the water outlet; a collar longitudinally adjustable on said rod; a float 70 slidable on said rod below the collar and adapted to lift said rod by engagement with the collar; and a collar adjustable longitudinally of the rod, and a fixed part engageable with the collar to limit the upward 75 movement of the rod.

Signed at Toronto this 1st day of December, 1919.

JOHN HENRY STANTON.
